United States Patent Office

Des. 188,360
Patented July 5, 1960

188,360

DRONE AIRCRAFT

Philip E. R. Brice, Amityville, N.Y., assignor to Republic Aviation Corporation, Farmingdale, N.Y., a corporation of Delaware

Filed May 20, 1959, Ser. No. 55,989

Term of patent 14 years

(Cl. D71—1)

Fig. 1 is a plan view of a drone aircraft embodying the present design;

Fig. 2 is a front elevation thereof; and

Fig. 3 is a side elevation thereof.

Both sides of the drone aircraft are substantially the same in appearance as indicated in Figs. 1 and 2.

What is claimed is:

The ornamental design for a drone aircraft, substantially as shown and described.
